(57) **CLAIM**

The ornamental design for a sleeve for an ultrasonic handpiece, as shown and described.

DESCRIPTION

FIG. 1 is a top, rear right perspective view of a sleeve for an ultrasonic handpiece showing our new design within its environment;

FIG. 2 is a top, rear right perspective view of the sleeve for an ultrasonic handpiece;

FIG. 3 is a top, rear left perspective view thereof;

FIG. 4 is a bottom, rear right perspective view thereof;

FIG. 5 is a bottom, rear left perspective view thereof;

FIG. 6 is a top, front right perspective view thereof;

FIG. 7 is a top, front left perspective view thereof;

FIG. 8 is a bottom, front right perspective view thereof;

FIG. 9 is a bottom, front left perspective view thereof;

FIG. 10 is a rear end view thereof;

FIG. 11 is a front end view thereof;

FIG. 12 is a left side elevational view thereof;

FIG. 13 is a right side elevational view thereof;

FIG. 14 is a top plan view thereof; and,

FIG. 15 is a bottom plan view thereof.

The broken lines shown in the figures depict portions of the sleeve for an ultrasonic handpiece that form no part of the claimed design. The additional broken lines shown in FIG. 1 depict environmental subject matter and form no part of the claimed design.

1 Claim, 9 Drawing Sheets
